ROLLER SKATE

Millard Collier, Vinita, Okla., assignor of one-half
to Cecil D. Stephens, Omaha, Tex.

Application November 26, 1948, Serial No. 61,957

2 Claims. (Cl. 280—11.19)

1

This invention relates to skates of the type which are supported by wheels.

An object of the invention is the provision of a skate having a platform which is supported by wheels of a particular construction so that the skates on the feet of the skater may be directed into close association with the adjacently disposed front wheels for frictionally contact to provide a braking action, the outer surfaces of the wheels being conical so that the surfaces of the inner wheels may come together progressively to retard the speed of the skater without causing an abrupt stop.

A further object of the invention is the provision of a skate which is of simple and durable construction and which is supported by wheels of approximately six inches in diameter with the outer faces of the wheels being in the form of a cone, the conical wheels being of sufficient strength to not only support the weight of the skater but to act as a brake to check the speed when the conical faces of at least a pair of the inner wheels are brought into frictional contact, the shape of the faces providing for an automatically progressive engagement to prevent sudden stops.

The invention is best understood from a consideration of the following detailed description in connection with the accompanying drawings forming part of the specification, nevertheless, it is to be understood that the invention is not confined to the disclosure but is susceptible of such changes and modifications as shall define no material departure from the salient features of the invention as expressed in the appended claims.

In the drawings:

Figure 1 is a side view of my improved skate,

Figure 2 is a plan view of the skate,

Figure 3 is a longitudinal vertical section of the skate,

Figure 4 is a fragmentary plan view of a pair of the skates showing the adjacent front wheels in braking relation,

Figure 5 is a fragmentary plan view of a pair of the skates with the inner adjacent front and rear wheels in braking relation,

Figure 6 is a fragmentary transverse vertical section taken along the line 6—6 of Figure 2,

Figure 7 is an enlarged fragmentary vertical section of the hub portion of a wheel, and

Figure 8 is a view in perspective of a connecting means for a strap.

Referring more particularly to the drawings, 10 designates a platform which is shaped to conform to the sole of a shoe. The platform is made

2

of metal and is provided with a plurality of openings 11 to decrease the weight thereof. A plurality of slots 12 are punched in the platform to form tongues which are bent to provide bearings 13 for axles 14 and 15.

Front wheels 16, 16' are mounted on the opposite ends of the axle 14 while rear wheels 17, 17' support the opposite ends of the axle 15.

Since all of the wheels are of identical construction 10 a description of a single wheel and its hub formation will suffice. Each wheel as illustrated in Figures 6 and 7 consists of an inner flat disk 20 and an outer conical disk 21 joined together in integral formation along the peripheries thereof by a grooved rim 22 which receives a rubber tire 23. A hub section 24 is attached integrally to the central portions of the disks. It will be noted from Figure 7 that the central portion 25 at the outer surface of the disk 21 is flat.

20 A bearing for the hub 24 includes a roller bearing 30 located between a pair of washers 31 the washer being mounted on a hollow portion 32 at the ends of axles 14 and 15, as clearly shown in Figure 7. A felt washer 33 which is saturated 15 with lubricating oil is disposed between each washer 31 and a relatively thin and stiff washer 34 or 34a. A disk 35 is received by the hollow end of the axle and abuts the inner faces of the washer 34 and the hub portion 24. These disks are welded at 35a to the axles.

25 A cap 36 has an outer conical face 37 and an inner flat face 38 in contact with the flat portion 25 of the disk 21. A rod 40 is received by the hollow end of the axle and has its outer end rigid with the inner face 38 of the cap 36. The inner 30 end of the rod is pinned at 41 to the axle.

Straps 45, 46 and 47 are employed for securing the heel portion of the shoe of the skater to the platform 10 while straps 48 and 49 are used to attach the toe portion of the foot of the skater to the forward end of each platform. As shown in Figure 8, a novel form of link 50 is employed for attaching the ends of the straps 45, 46, 48 and 49 to the skate. The links which are formed of metal have a passage 51 to receive the axles 14 and 15 and a slot 52 to receive a loop at the ends of the various straps.

The wheels are approximately six inches in diameter or are of a size which will prove satisfactory to the skater. As shown in Figures 4 and 5. The facing wheels at the inner sides of the pair of skates may be brought together so that the conical faces of the wheel will move into bearing engagement to effect a braking action. On the other hand, both wheels at the adjacent

faces of a pair of skates may be brought together for increasing the braking action.

What I claim:

1. In a skate including a platform, a pair of spaced axles arranged transversely of said platform and supported on the under surface thereof, and a wheel having a tire thereon rotatably supported on each end of each of said axles, the improvement comprising providing the exterior face of each of said wheels with a projection in the form of a cone, said cone extending outwardly of and beyond the outer face of the tire of the adjacent wheel whereby the conical projection of one wheel of one skate of a pair of skates may be brought into bearing engagement with the conical projection on a facing wheel of the other skate of said pair of skates to effect a braking action.

2. In a skate including a platform, a pair of spaced axles arranged transversely of said platform and supported on the under surface thereof, and a wheel having a tire thereon rotatably supported on each end of each of said axles, the

5 improvement comprising providing the exterior face of each of said wheels with a projection in the form of a cone, said cone extending outwardly of and beyond the outer face of the tire of the adjacent wheel and the apex of said cone lying along the longitudinal axis of the axle on which it is supported, whereby the conical projection of one wheel of one skate of a pair of skates may be brought into bearing engagement with the conical projection on a facing wheel of the other skate of said pair of skates to effect a braking action.

MILLARD COLLIER.
